UNITED STATES PATENT OFFICE.

JOHN R. ROGERS, OF BROOKLYN, NEW YORK, ASSIGNOR TO MERGENTHALER LINOTYPE COMPANY, A CORPORATION OF NEW YORK.

TYPOGRAPHICAL DISTRIBUTING MECHANISM.

Application filed September 18, 1926. Serial No. 136,233.

This invention relates to typographical distributing machines, such as linotype machines of the general organization represented in U. S. Letters Patent to O. Mergenthaler, No. 436,532, wherein circulating matrices are released from a magazine in the order in which their characters are to appear in print and then assembled in line, the composed line transferred to the face of a mold, the mold filled with molten metal to form a slug or linotype against the matrices which produce the type characters thereon, and the matrices thereafter returned through a distributing mechanism to the magazine from which they started. In some machines, such as the commercial model 9, where matrices may be drawn from several magazines and mixed together in the same line, the distributing mechanism includes a primary distributor which first sorts the matrices according to font, and a plurality of main distributors which thereafter sort the matrices of the individual fonts according to character and restore them to their proper channels in the magazines. With this type of distributing mechanism, the matrices, after font separation, pass down chutes or tubes and enter so-called lower distributor boxes wherein they are guided upon inclined rails into engagement with reciprocating pawls or escapements, which feed them one at a time to the main distributors. In order that these pawls or escapements may cooperate properly with the matrices, the latter are provided in their bottom edges with central notches which necessarily vary in shape and depth according to the thickness of the individual matrices. Besides adding to the cost of production, such notches in the matrices materially limit the space ordinarily required for the regular font notches and, moreover, seriously weaken the matrices, especially when the latter are formed with other necessary cuts or notches. Furthermore, matrices comprising fonts used on other machines, such as those of the single distributor class, are excluded from use on machines of the multiple distributor class described, since they do not have the required central notches.

The present invention is intended to obviate the foregoing difficulties and contemplates certain improvements whereby the distributing mechanism may receive and han-

dle matrices of all fonts whether they have or have not the objectionable central notches referred to. To this end, each of the lower distributor boxes is provided with an escapement device arranged preferably to cooperate with the upper ends of the matrices, and which device not only serves its primary purpose of feeding the matrices one by one to the distributor screws, but also acts to accelerate the delivery of the individual matrices to the screws. In the embodiment illustrated there are employed two cooperating escapement members, one being yieldably mounted and provided with a pair of depending fingers which serve to arrest the gravitating matrices by their upper projecting ears, and the other a rotatable releasing dog operated independently of its associate member and acting to depress the matrices out of their arrested position in effecting their separation and escape to the screws.

In the accompanying drawings the invention has been shown merely in preferred form and by way of example, and as applied to the specific type of distributing mechanism indicated. However, many changes and variations may be made therein and in its mode of application, which will still be comprised within its spirit. It is to be understood, therefore, that the invention is not limited to any specific form or embodiment, except in so far as such limitations are specified in the claims.

Referring to the drawings:

Fig. 1 is a rear elevation of the receiving end of a multiple distributor showing the lower distributor box broken away and equipped with the present improvements;

Fig. 2 is a detached perspective view of the escapement device and its supporting block;

Fig. 3 is a vertical transverse section taken on line 3-3 of Fig. 1; the upper box being omitted for the sake of clearness;

Fig. 4 is a fragmentary view of the lower box with its rear side plate removed and showing the escapement device in the act of releasing a matrix; and

Fig. 5 is a detail perspective view of the matrix arresting escapement member.

After casting, the matrix line is transported to the upper distributor box A where the individual matrices are successively detached from the line by the lifting finger 113

A¹ for delivery to the upper or lower distributor, as the case may be. The two distributors are identical in construction, each comprising a longitudinally ribbed bar B and a set of conveying screws B¹ which carry the matrices therealong. After the matrices are detached from the line, they are presented to the conveying screws B¹ of the upper distributor but, before they reach the corresponding distributor bar B, they are subjected to the action of the font selecting bridge C which is adapted to cooperate with the lower ends of the matrices and control their delivery according to font to the upper or lower distributor. The matrices X are of the usual construction, each being formed at its four corners with the projecting ears x and at its upper end with distributing teeth x¹. The matrices of one font (those delivered to the lower distributor) are formed at their lower ends with the ordinary font notches x², while the matrices of the other font (those delivered to the upper distributor) are without such notches or have them located in a different position along their bottom edges. Consequently, when the matrices are presented to the selecting bridge C, those without the font notches are supported by said bridge at such level that their distributing teeth x¹ are caused to engage the upper distributor bar B; while those of the other font, due to the presence of the notches x², straddle the bridge C and drop to a lower level so that their distributing teeth will avoid engagement with the upper distributor bar. These latter matrices, when straddling the selecting bridge are supported by their upper projecting ears upon the guide rails A² and are carried along these rails and dropped into the chute C¹ leading downwardly to the lower distributor box D. The matrices pass by gravity through the box D wherein they are supported by the inclined rails D¹, and are fed one by one under the control of an escapement, into the threads of the conveying screws B¹ of the lower distributor, whence they are carried along the associated bar B for final distribution.

The parts so far described, except as hereinafter pointed out are or may be of any well known or approved construction, and in themselves constitute no part of the present invention, which is directed primarily to an improved form of escapement for the lower distributor box D. In the embodiment illustrated the improved escapement is arranged to cooperate with the upper ends of the gravitating matrices and acts to control their passage, one at a time, into position to be picked up by the screws, irrespective of the presence or absence of the objectionable central notches hereinbefore mentioned. As shown, the escapement comprises a matrix arresting member E and a ma-

trix releasing dog E¹ mounted adjacent each other in a supporting block D². The arresting member E is pivoted upon a sustaining rod or pin e and is formed with an upper projection E² and a pair of depending fingers E³, the latter being arranged so as to engage the matrices by their upper projecting ears x as they slide down the box rails D¹. A spring E⁴ interposed between the projection E² and the upper inclined wall of the supporting block D² controls the pivotal action of the member E and is sufficiently strong to withstand the impact of the descending matrices. The releasing dog E¹ is journaled in the side walls of the block D² as at e¹, and is formed with a longitudinal lip portion E⁵. It will be noted (see Fig. 1) that the lip E⁵ projects slightly beyond the fingers E³ so that, when the dog is turned or rotated to the position shown in Fig. 4, a matrix arrested by the fingers will be engaged by the lip and pushed thereby down the rails D¹ toward the pick-up position of the distributor screws. This feature is desirable since it insures the delivery of the matrices to the screws quicker and at more regular intervals than would be the case if gravity alone were depended upon, as it might be, it being understood that the thinner matrices being lighter and more liable to slight interferences than those of the thicker or heavier variety, are frequently delayed and hence are more apt to cause clogging and stoppage of the distributor. In order that only one matrix may be engaged at a time by the dog E¹, the arresting face of the fingers E³ is spaced from the end of the lip E⁵ a distance slightly less than the thickness of the thinnest matrix. This relation of the parts is maintained in the present instance by a set screw E⁷ which opposes the spring E⁴ and sustains the arresting member against the tension thereof.

In the present instance the dog E¹ is operated from the rocker arm A³ of the lifting finger A¹ which is, in turn, actuated in the customary way by the cam B² secured to the end of one of the upper distributing screw spindles, the desired motion being imparted to said dog through the vertical link E⁸ connected to the free end of a crank arm E⁶ fast to one of the journal studs e¹. In this connection it will be observed by reference to Fig. 3 that the two distributors are driven in synchronism and at the same rate of speed by means of a chain F, as indicated, or a train of gears, the lower screws being so set in relation to the operation of the dog E¹ that the receiving ends of the screw threads will be properly positioned to engage a matrix as it reaches the pick-up position. It will also be noted that the supporting block D² is sustained independently of the box D by means of a clamping screw 130

D³ and hence permits the removal of the box in the usual way D⁴ without disturbing the escapement and its operating connections.

The operation will now be clear. As the dog E¹ is rotated downwardly or clockwise by the arm A³ an arrested matrix will be engaged by the lip E⁵ and pushed thereby down the inclined rails D¹, the arresting fingers E³ being swung to the left against the tension 10 of the control spring E⁴ by the escaping matrix until the latter is moved out of engagement therewith and is free to pass to the pick-up position. The fingers E immediately resume their normal position and 15 act to arrest the following matrix which is momentarily held back by the lip E⁵. (See Fig. 4.) On the return movement of the arm A³, the dog E¹ is rotated upwardly or anti-clockwise to its original position and 20 the lip E⁵ again located in proper relation to the fingers E³ to engage said following matrix which now becomes the leading one. While the actual operation takes place as just described, the movements of the parts 25 are very rapid, the escapement being actuated at each rotation of the distributing screws, so as to feed the matrices thereto, one at a time, in a definite and timed relation.

As previously stated, the invention has 30 been shown herein only in the preferred form and by way of example, and obviously it is susceptible of many modifications and variations without departing from its scope. For example, the matrix releasing dog E¹, 35 instead of being oscillated back and forth in the above described manner, could be made to rotate continuously in causing its lipped portion E⁵ to engage the successive matrices, it being a simple matter to synchronize the rotation of the dog with that 40 of the distributor screws in carrying out such an operation. Again, while it has been found to be thoroughly satisfactory in practice to cause the matrix as it is depressed by the releasing dog to displace the arresting fingers E³, the latter might readily be controlled or operated directly from the releasing dog, so as to be moved clear of the depressed matrix when the dog assumes its 45 downwardly turned position, where it is effective in holding back temporarily the following matrices. As a matter of fact it would be possible to arrange the arresting fingers stationarily and rely upon an end- 50 wise shifting of the individual matrices by the oscillating or rotating dog in effecting their release, as for instance, if the dog should be arranged to engage the lower ends of the matrices instead of their upper ends, as might be done. These and various 55 other changes will readily suggest themselves to those skilled in the art, hence it should be understood that the invention is not limited to any specific construction or 60 arrangement of the parts excepting in so far

as such limitations are specified in the appended claims.

Having thus described my invention, its construction and mode of operation, what I claim and desire to secure by Letters Patent 70 of the United States is as follows:

1. In a typographical distributing mechanism comprising a distributor bar and a set of matrix conveying screws, the combination of an inclined guide means along 75 which the matrices gravitate toward the screws, and an escapement device arranged to cooperate with the upper ends of the matrices, said device comprising a yieldable member for arresting the descending matrices, and means operated independently of 80 said member for depressing the arrested members out of engagement therewith in effecting their escape, one at a time, into position to be picked up by the screws. 85

2. In a typographical distributing mechanism comprising a distributor bar and a set of matrix conveying screws, the combination of an inclined guide means along which the matrices gravitate toward the screws, and an escapement device arranged to cooperate with the upper ends of the matrices, said device comprising a yieldable member for arresting the descending matrices, and a rotatable dog acting to depress the arrested 90 matrices out of engagement with the arresting member and serving to accelerate their delivery to the screws. 95

3. In a typographical distributing mechanism, comprising a distributor bar and a 100 set of matrix conveying screws, the combination of an inclined guide means along which the matrices gravitate toward the screws, and an escapement device arranged to cooperate with the upper ends of the matrices, said device comprising a pivoted member for arresting the descending matrices, a spring for holding said member in normal position, and an oscillatory member mounted adjacent the arresting member for depressing the arrested matrices out of engagement 105 therewith, in effecting their escape, one at a time, into position to be picked up by the screws. 110

4. In a typographical distributing mechanism, comprising a distributor bar and a set of matrix conveying screws, the combination of inclined guide means along which the matrices gravitate toward the screws, and an escapement device arranged to cooperate 120 with the upper ends of the matrices, said device comprising a pair of yieldable fingers for arresting the descending matrices by their upper projecting ears, and a releasing member arranged to engage the arrested 125 matrices and acting to depress them out of engagement with the fingers in effecting their escape, one at a time, into position to be picked up by the screws. 130

5. In a typographical distributing mecha-

- nism, comprising a distributor bar and a set of matrix conveying screws, the combination of inclined guide means along which the matrices gravitate toward the screws, and an escapement device arranged to cooperate with the upper ends of the matrices, said device comprising a pair of yieldable fingers for arresting the gravitating matrices by their upper projecting ears and a rotatable releasing dog associated therewith, said parts being mounted independently of each other, but arranged to cooperate in effecting the escape of the matrices, one at a time, into position to be picked up by the screws, said dog in its upper position standing clear of the descending matrices, but acting during its downward turning movement to depress the leading matrix and hold back the following matrices, and said arresting fingers in the upper position of the dog serving to arrest the leading matrix in engaging relation thereto, and in the lower position of the dog being moved out of the way by the depressed matrix to permit its escape.
6. In a typographical distributing mechanism comprising a distributor bar and a set of matrix conveying screws, the combination of inclined guide means along which the matrices gravitate toward the screws, and an escapement device arranged to cooperate with the upper ends of the matrices and acting to control their passage, one at a time, into position to be picked up by the screws, said device comprising a spring-actuated arresting member pivotally mounted and formed with a pair of depending fingers arranged in the path of the upper projecting ears of the matrices, and a releasing member rotatably mounted adjacent the arresting member and operative to depress the leading matrices in effecting their escape to the screws.
7. In a typographical distributing mechanism comprising a distributor bar and a set of matrix conveying screws, the combination of inclined guide means along which the matrices gravitate toward the screws, and an escapement device arranged to cooperate with the upper ends of the matrices, said device comprising a yieldable member for arresting the descending matrices, a releasing member acting to depress the arrested matrices, one at a time, out of engagement with the arresting member and adjusting means for maintaining the two said members in a predetermined relation to each other.
8. In a typographical distributing mechanism, the combination of upper and lower distributors, each comprising a distributor bar and a set of matrix conveying screws, a reciprocating finger for feeding the matrices, one at a time, to the upper set of screws, a font separator whereby matrices of a certain font are fed to the upper distributor and those of a different font re-

leased toward the lower distributor, and an escapement device actuated by said reciprocating finger for controlling the passage of the gravitating matrices, one at a time, into position to be picked up by the lower set of screws.

9. In a typographical distributing mechanism, the combination of upper and lower distributors, each comprising a distributor bar and a set of matrix conveying screws, a reciprocating finger for feeding the matrices, one at a time, to the upper set of screws, a font separator whereby matrices of a certain font are fed to the upper distributor and those of a different font released to gravitate toward the lower distributor, and an escapement device actuated by said reciprocating finger for controlling the passage of the gravitating matrices, one at a time, into position to be picked up by the lower set of screws, said device comprising a yieldable member for arresting the gravitating matrices and a releasing member for depressing them out of engagement with the arresting member in effecting their escape.

10. In a typographical distributing mechanism comprising a distributor bar and a set of matrix conveying screws, the combination of inclined guide means along which the matrices gravitate toward the screws and an escapement device arranged to cooperate with the upper ends of the matrices and acting to control their passage, one at a time, into position to be picked up by the screws, said device comprising a resilient member E formed with the depending arresting fingers E³ and the rocking dog E¹, having the matrix engaging lip E⁵ arranged in operative relation to said fingers, substantially as shown and described.

11. In a typographical distributing mechanism comprising a distributor bar and a set of matrix conveying screws, the combination of an inclined guide means along which the matrices gravitate toward the screws, an escapement device arranged to cooperate with the gravitating matrices and acting to control their passage, one at a time, into position to be picked up by the screws, said escapement device comprising a rotatable dog formed with a lip portion adapted to engage the individual matrices and shift them endwise in effecting their release.

12. In a typographical distributing mechanism comprising a distributor bar and a set of matrix conveying screws, the combination of an inclined guide means along which the matrices gravitate toward the screws, an escapement device arranged to cooperate with the gravitating matrices and acting to control their passage, one at a time, into position to be picked up by the screws, said escapement device comprising a member for arresting the descending matrices and a ro-

tatable dog formed with a lip portion adapted to engage the individual matrices and shift them endwise to clear the arresting member in effecting their release.

5 13. In a typographical distributing mechanism comprising a distributor bar and a set of matrix conveying screws, the combination of an inclined guide means along which the matrices gravitate toward the screws, and an escapement device arranged to cooperate with the upper ends of the matrices and acting to control their passage, one at a time, into position to be picked up by the screws, the said escapement device comprising a yieldable matrix arresting member and an oscillatory matrix releasing dog, said dog in its upper position standing clear of the descending matrices, but acting during its downward movement to effect the release 10 of the leading matrix and to hold back the following matrices, the said arresting member in the upper position of the dog serving

to arrest the leading matrix and in the lower position of the dog being moved clear of the said matrix to permit its escape.

25

14. In a typographical distributing mechanism comprising a distributor bar and a set of matrix conveying screws, the combination of a removable distributor box formed with inclined guide rails on which the matrices gravitate toward the screws and an escapement device arranged to cooperate with the gravitating matrices and acting to control their passage, one at a time, into position to be picked up by the screws, the said escapement device being mounted independently of the distributor box so as to permit the latter to be removed without disturbing the escapement device or its operating connections.
